No. 876,050.

PATENTED JAN. 7, 1908.

H. J. FOLTZ.

CONVERTIBLE WINDOW SASH.

APPLICATION FILED MAR. 3, 1906.

UNITED STATES PATENT OFFICE.

HARRY J. FOLTZ, OF AKRON, OHIO.

CONVERTIBLE WINDOW-SASH.

No. 876,050.

Specification of Letters Patent.

Patented Jan. 7, 1908.

Application filed March 3, 1906. Serial No. 303,968.

To all whom it may concern:

Be it known that I, HARRY J. FOLTZ, a citizen of the United States, residing at Akron, in the county of Summit and State of Ohio, have invented certain new and useful improvements in Convertible Window-Sash; and I do hereby declare the following to be a full, clear, and exact description of the invention, such as will enable others skilled in the art to which it pertains to make and use the same.

My invention relates to convertible window sashes, and has for its object the forming of the stiles of the sash, at both sides, in two parts; one of the parts engaging the window frame, and the other part being pivotally secured to the sliding portion, the lower being arranged in such a manner that the window, while adapted to slide in its ways in the window frame, can be rotated, or, more properly speaking, operated so as to swing inward and outward on its pivotal connection, thus allowing the opening of the window in this manner for the purpose of cleaning it, and its glass on the exterior, and eliminating the danger resulting from the necessity of exposing the person on the outside of the building, and the liability of falling, or otherwise injuring the person.

Another object of my invention is to so unite the two parts of the stiles of the sash that while pivoted together in such a manner that the portion that holds the glass can be operated at any suitable angle for ventilating purposes, or entirely reversed for cleaning purposes, the joint formed by the division of the stiles is sealed or overlapped by a device which also forms a locking mechanism, to hold the two parts firmly in alignment.

Still another object of this invention is to simplify the construction so that any ordinary person can easily understand and manipulate it.

With the above objects in view, my invention consists in dividing the stiles of a window sash, and providing a locking means for alining both parts.

My invention further consists in providing a divided sash frame with locking means which will aline both parts and over-lap or seal the dividing line or joint.

My invention still further consists in the construction and details of construction which will be hereinafter fully set forth and claimed.

In the drawings Figure 3 is an isometric

view of a portion of a window frame, and a portion of the upper and lower sash, illustrating the construction and application of my invention when the same is constructed and assembled according to my invention. Fig. II is a cross sectional view taken through the pivotal connection between both parts of the sash-frame, showing more clearly the manner of assemblage, operation, and connection of the parts when the same is constructed as illustrated in Fig. I. Fig. III illustrates the parts of the sash, with the portion holding the glass swung at an angle to the other portion.

A represents the pulley piece, with the upper parting strip A', and the inner beading B, which may be of any suitable construction or arrangement. This frame A does not constitute any part of my invention excepting as a means for retaining the sash in position, and if necessary allowing the sash to be raised or lowered, and hence in certain cases the parting strip A' and the pulley piece A with the other auxiliaries, may be dispensed with.

The important feature of my invention is embodied in the sash itself.

C represents that part of the sash which engages the window frame, either in a stationary manner or so as to be raised or lowered.

C' represents that part of the sash within which the glass G of the window is held.

The parts C, C' are separate, being joined together by a pivot P, (see Fig II,) of suitable formation to allow the inner portion C', to operate in relation to the part C.

The pivot P is preferably centrally located in relation to the length of the sash-bar or stile, but this is not absolutely essential, but a preferable construction. It will thus be seen that in case the window is constructed as illustrated in Fig. I, that, by lowering the upper sash or raising the lower sash, so as to free them from the upper and lower jams of the window frame, that the upper sash can be swung inward and thence downward, and reversed to the extent of presenting the top face of the glass which is formerly of the exterior of the window, inward for the purpose of cleaning it.

In order to form a sash which has all the advantages of an ordinary sash, besides the advantages hereinbefore mentioned, I have provided a locking means which comprises a sliding portion E, connected preferably to

the portion C' of the sash; this piece E being shown in the drawings and provided with elongated slots e, e, and binding screws F, which pass through the slots and from thence 5 into the portion C' of the sash in such a manner that they may be loosened and tightened and thus loosen and tighten the sliding piece E. It will be observed by reference to the drawings that the slide E is so 10 formed that when it is slid to the joint c, it will overlap the same and bind the sash parts C, C' into alinement.

In order to further provide a perfect lock and sash, I have provided, as illustrated in 15 the drawings, a keeper-piece K which flares or projects in from the piece C, at its inner face in such a manner as to receive the slide piece E. The juncture or meeting portions of the two pieces E and K being so formed 20 that a sealed connection is provided between them. This sealed connection performs the double function of preventing the rattling of the parts in relation to each other and forming a perfect dust and air seal.

25 The parts E and K may be formed in any suitable manner so that they will interlock in the manner, and for the purpose above set forth, and it is obvious that certain of these parts and their relation to each other may be modified, as may also other details, such as 30 the pivot pin p, and I do not wish therefore to limit my invention to the construction shown and hereinabove set forth.

In the construction of a sash of the type 35 hereinabove set forth and shown in the

drawings, many apparent and obvious advantages are attained, as its simplicity of construction and perfect operation of the parts, eliminating complicated devices and operations.

As hereinabove set forth, while I have shown and described my invention as applied to a double sash window, and I have shown details of construction as I consider them best adapted to perform that function in 45 relation to each other, I do not wish to be limited to these details, which as hereinabove stated can and will be modified to adapt them to position and circumstances.

What I claim is.

A slideable and tiltable window sash having its stiles divided vertically into outer sliding members and inner tilting members, a pivot connecting each pair of members, a keeper strip disposed longitudinally on the rear side 55 of each sliding member and having its inner longitudinal portion flared away therefrom, and a transversely - slideable locking strip mounted longitudinally on the rear side of each tilting member, being arranged in locking position to overlap the two members and engage tightly behind the flared portion of said keeper strip.

Signed at Cleveland in the county of Cuyahoga and State of Ohio, this 26 day of 65 August, 1905.

HARRY J. FOLTZ.
